E. L. KELLER

FLUSH VALUE

APPLICATION FILED APR. 14, 1918.

1,337,177.

Patented Apr. 13, 1920.

UNITED STATES PATENT OFFICE.

EDWARD L. KELLAN, OF CHICAGO, ILLINOIS.

FLUSH-VALVE.

1,337,177.

Specification of Letters Patent.

Patented Apr. 13, 1920.

Application filed April 1, 1916. Serial No. 88,230.

To all whom it may concern:

Be it known that I, EDWARD L. KELLAN, a citizen of the United States, and a resident of Chicago, in the county of Cook and State 5 of Illinois, have invented certain new and useful Improvements in Flush-Valves; and I do hereby declare that the following is a full, clear, and exact description thereof, reference being had to the accompanying 10 drawings, and to the characters of reference marked thereon, which form a part of this specification.

This invention relates to improvements in flush valve devices for supplying a desired 15 volume of liquid through a desired interval of time from a source of liquid supply under pressure to a place or places where the liquid is to be used. The present invention relates to that type of valve commonly 20 known as semi-automatic wherein the valve is opened for the flow of liquid therethrough through the instrumentality of a manually operable device and is automatically closed by reason of differential pressures on the 25 valve parts.

Among the objects of the invention are to improve the means employed in the valve to produce the after fill in the connected bowl and to provide in this connection a construction and arrangement of parts associated therewith as will insure the washing 30 away of particles tending to cling to the valve seat and injure or destroy the seat packing.

Other objects of the invention are to improve and simplify valve structures of this general character and the invention consists in the combination and arrangement of the parts shown in the drawings and described 35 in the accompanying specification and set forth in the appended claims.

As shown in the drawings:—

Figure 1 is a vertical axial section of the flush valve embodying my improvements, 40 said section being on the line 1—1 of Fig. 3.

Fig. 2 is a horizontal section on the line 2—2 of Fig. 1.

Fig. 3 is a vertical section of the valve in its open position, said section being in a 45 plane at right angles to the plane of the section shown in Fig. 1.

As shown in the drawings 9 designates the valve casing, 10 its inlet branch and 11 its outlet branch. The upper end of the cas-

ing is closed by a screw threaded plug 12. 55 The casing is provided near its inlet branch with an internal flange 14 on which is formed an upwardly facing annular body seat 15. 16 designates as a whole the main valve which has a seat face, preferably formed on 60 a yielding ring 17, to engage the body seat. The said ring 17 is confined between the body of the valve 16 and a plate 18 which latter is provided with an externally screw threaded hollow stem 19 that extends upwardly into a hollow neck 20 that is made integral with and extends upwardly from the body of the valve 16; said neck being internally screw threaded to engage the screw threads of the stem to thereby afford 70 a clamping pressure on the seat ring 17 between the parts 16 and 18. The valve is guided in its opening and closing movement by a suitable guide cage 23 which fits closely within the hollow body seat flange 75 14. Carried by the upper end of the neck 20 is a motor piston 25 of larger diameter than the valve 16. Said piston closely fits within the enlarged bore of the casing above the inlet opening, thus dividing the cylinder into upper and lower pressure chambers. 80 The piston is made hollow whereby the upper pressure chamber communicates with the interior of the hollow neck 20.

The upper pressure chamber communicates with the inlet side of the valve through a by-pass 26 which opens at its lower end into the lower pressure chamber and communicates at its upper end through a lateral passage 27 with the upper pressure chamber. 85 The flow of liquid through the by-pass is controlled by a valve formed on the inner reduced end of a screw threaded plug 28 which extends into the lateral passage 27 and is screw threaded in a hollow lug or 90 boss 29. Said boss is closed at its outer end by a stuffing box through which the plug extends whereby the plug is accessible to adjust the opening 27. The inner end of the plug 28 which extends into the opening 27 95 is obliquely cut away or scarfed at one side a sufficient distance from the end thereof to provide a restricted liquid passage between the upper end of the by-pass 26 and the upper pressure chamber; and the area of this 100 passage may be increased or decreased by turning the plug in the proper direction. By scarfing or tapering the inner end of the 105

plug sharp edges are produced which serve, upon rotating the plug backwardly and forwardly a few times in the opening 27, to clear the opening of sediment which may 5 tend to lodge therein and thereby clear the passage for free flow of liquid therethrough. With this construction it becomes unnecessary to entirely remove the plug to clear the opening.

10 At the upper end of the hollow stem 19 is formed an annular seat which coöperates with a starting or release valve 30 carried by the upper end of a valve stem 31 which latter extends through the hollow stem 19 15 and the hollow main valve and through the guide cage 23 for the main valve. The starting or release valve is held against its seat by a spring 32 which is interposed between the main valve and a suitable shoulder or 20 abutment 33 on the stem. Said spring 32 is preferably conical, being made larger at its upper end, in order to secure a wide bearing against the main valve, thereby tending to hold the starting valve squarely on its seat 25 and avoid the latter valve tilting on said seat.

The said starting valve is operated by means of a crank arm 34 arranged below the stem 31 and in line therewith, said crank 30 arm being carried by a rock shaft 35 which extends outwardly through a suitable stuffing box 36 in the side wall of the casing and may be provided with any suitable form of 35 manual controlling device, such as a lever. 35 The said crank arm 34 is curved on its upper face which engages the lower end of said stem 31 and the lower end of said stem may be likewise rounded so as to effect a direct upward lift of the starting valve with small 40 friction and a minimum tendency to tilt the auxiliary valve.

When the parts are in the position shown 45 in Fig. 1 the inlet pressure is equalized on both sides of the piston 25 and the inlet pressure acting against the top of the main 50 valve 16 holds the latter against its seat. When the starting valve is lifted off its seat liquid from the upper pressure chamber is free to pass to the outlet side of the valve 55 and the effect of this release is to reduce the pressure above the piston 25 and to thereby permit the differential pressures, which act on the lower side of the piston 25 and the upper side of the main valve, to raise or open the latter so as to permit the flow of liquid through the valve.

After the valve is thus opened the pressures on the upper and lower sides of the piston 25 are gradually equalized through 60 the by-pass 26 and, upon the equalization of the pressures on the upper and lower sides of the piston, the inlet pressure acts on the main valve to close it.

The rapidity of flow of the liquid through 65 the by-pass 27 and the consequent opening

period of the valve is governed by the adjustment of the screw threaded plug 28; the larger the effective area of the opening 27 the shorter will be the period in which the main valve remains open and vice versa. 70

Arranged across the lower end of the by-pass 26 is a screen 40 by which to protect the by-pass valve against solid matter which is carried in suspension in the flushing liquid. The location of the screen shown is 75 advantageous inasmuch as the rush of liquid against the same during the flushing period serves to keep the screen clean.

Referring now to my improvement to provide a restricted flow of liquid through the 80 valve after the main flow has practically ceased and thereby provide an after fill in the bowl, the same is made as follows:

42 designates a shell or tube which surrounds the main valve and its hollow stem 85 and normally rests at its lower edge against the upper face of the internal annular flange 14 of the casing. Said shell 42 guidingly engages a series of angularly separated ribs 43 on the hollow neck 20 and has free vertical movement relatively to said valve stem. The radius of the main valve 16 is slightly less than that of the ribs so that thereby is provided between the periphery of the main valve and said shell an annular space 44 95 through which liquid may pass in restricted volume.

The said shell carries a plurality of inwardly projecting lugs 45, herein shown as having the form of short screws that are 100 screw threaded through openings 46 in the shell. These lugs are located in the path of the valve 16. The relation of the parts is such that the shell 42 is stationary during the first part of the opening movement of 105 the main valve. When the rising main valve engages the lugs 45 of the shell, the shell rises with the main valve during the remaining portion of its opening movement. As a result of this construction the seat 15 110 and the seating face 17 of the main valve are not subjected to extreme cutting action of the liquid at the first opening of the main valve inasmuch as the flow of the liquid is restricted to the volume which may pass 115 downwardly through the shell and through the narrow annular opening 44 and also between the lower end of the shell and the upper face of the flange 14; these restricted passages receiving the principal cutting 120 action of the liquid.

When the main valve is raised to its full height, as indicated in dotted lines in Fig. 3, it will be noted that the shell 42 extends considerably below the plane of the seating 125 face of said valve. Therefore, during the closing movement of the valve, the lower edge of said shell first engages its seating surface formed on the upper face of the flange 14 and thereby cuts off the full flow 130

of the liquid, but permitting an after flow volume such as will escape beneath the shell and through the annular passage 44. The parts are so adjusted that a sufficient volume 5 of liquid has passed through the valve for the practical flushing operation desired when the shell 42 strikes the flange 14, and during the remaining portion of the closing movement the liquid which escapes through the 10 valve will be sufficient to produce the desired after fill in the bowl.

A further advantage rising out of the use 15 of the cutting off shell thus described is that the areas of the passages for the after flow are so small as to prevent the passage there- 20 through of solid matter of substantial dimension carried by the liquid and the after flow will be sufficient to wash away any solid matter which may tend to cling to the seat. 25 Thereby is avoided the liability of pipe chips or any other solid matter being caught be- 30 tween the valve and its seat so as to prevent full closing of the valve with a result of causing the valve to leak or injure the seat- 35 ing faces.

The volume of the after flow may be regu- 40 lated by raising or lowering the lugs 45. This may conveniently be effected by pro- 45 viding the shell with a number of openings 50 46 located in different vertical planes which are screw threaded to receive the screw threaded lugs 45. When the lugs occupy the lower openings 46 the duration of the after flow will be shortest and when said 55 lugs occupy the upper openings 46 the duration of the after flow will be greatest as will be apparent.

In some instances it may be desirable to 60 provide the casing with a resilient buffer such as is indicated by 47. In case such buffer be required it may be conveniently at- 65 tached to the boss 29 by means of a screw threaded sleeve 48 screw threaded to the boss and provided with an inturned edge 49 70 that engages over the buffer to hold it in place. When it is desired to adjust the valve plug 28, said buffer may be readily removed by unscrewing the sleeve 48 as will be apparent.

75 The shoulder 33 against which the lower end of the spring 32 bears is preferably en- 80 larged, as shown, in order that the flow of water striking the same may assist to close the main valve, in the event that it tends to stick in the casing because of too close a fit or because the pressure of the source of sup- 85 ply is so low as to render the equalization of the pressures through the by-pass 26 sluggish.

90 It will be understood that the structural details illustrated may be varied somewhat within the spirit and scope of the claims hereto appended.

I claim as my invention:—

95 1. A flush valve device having an inlet

and an outlet, a main valve piece which con- 10 trols the flow of the flushing liquid and pro- 15 vided with an upstanding neck smaller than the main valve piece, means for opening the main valve piece, means constructed to auto- 20 matically close it, and means to produce a restricted after flow subsequent to cutting off the main flushing flow, said latter means comprising a shell surrounding said main valve piece and the neck, with a restricted 25 fluid passage between the shell and valve piece, said shell being open at the top for liquid flow from the inlet and being move- 30 able relatively to the main valve piece and means carried by the shell abreast the neck 35 and normally spaced from, but in the path of, the main valve piece as it rises for causing the shell to move with the main valve piece during the extreme opening movement 40 of the latter.

2. A flush valve device comprising a cas- 45 ing having an inlet and outlet, with an internal flange between them formed to pro- 50 vide a seat, a valve piece coöperating there- 55 with and provided with an upstanding neck 60 having guide ribs, an open top shell sur- 65 rounding the valve piece and neck and guid- 70 ing engagingly said ribs, and normally resting on said flange and movable rela- 75 tively to the valve piece, there being a re- 80 stricted liquid passage between the shell and the valve piece, and a projection on the shell abreast the neck normally spaced from, but in the path, of the valve piece and adapt- 85 ed, when the valve piece is partially raised, 90 to be engaged thereby, whereby the shell is thereafter raised with the valve piece, said shell engaging said flange prior to the final closing movement of the valve piece.

3. A flush valve device comprising a cas- 95 ing having an inlet and outlet, with an internal flange between them formed to pro- 100 vide a seat, a valve piece coöperating there- 105 with, an open top shell in the path of the liquid flow surrounding the valve piece and 110 normally resting on said flange and movable relatively to the valve piece, there being a restricted liquid passage between the shell and the valve piece, a projection from the 115 wall of said shell spaced above and in the path of the valve piece and adapted, when the valve piece is partially raised, to be engaged thereby, whereby the shell is thereafter raised with the valve piece, said shell en- 120 gaging said flange prior to the final closing movement of the valve piece, and means for vertically adjusting said projection on said shell.

4. A flush valve device comprising a cas- 125 ing provided with an inlet and an outlet, a main valve piece which controls the flow of the flushing liquid through the shell and having an upstanding reduced neck, an auxiliary valve within the neck which controls the main valve piece, the valve casing being 130

- provided with an internal flange between the inlet and outlet on which is formed a seat to coöperate with the main valve piece, a shell surrounding the main valve piece and its said neck, with a restricted liquid passage between it and the main valve piece and adapted to normally rest on the internal flange of the casing, said shell being spaced from said neck and the passage between the shell and neck being open to the flow of liquid through said valve, said shell being movable relatively to the main valve piece, and a projection on the shell extending toward the neck and spaced from the main valve piece and adapted to be engaged by the main valve piece when the latter rises.
5. A flush valve device comprising a casing, a main valve which controls the flow of the flushing liquid and having an upstanding reduced portion, an auxiliary valve which controls the main valve, the valve casing being provided with an internal flange on which is formed a seat to coöperate with the main valve, a shell surrounding the main valve and its upstanding portion, with a restricted fluid passage between said shell and valve, said shell being adapted to normally rest on said internal flange and being movable relatively to the main valve and provided with a plurality of vertically spaced openings, and a stud adapted to be engaged in either one of said openings and to be engaged by the main valve when the latter rises.
6. A flush valve device comprising a casing provided with an inlet and an outlet and with an internal seat between them, a reciprocating unit within the casing comprising a main valve piece to engage said seat, a reduced upstanding hollow member and a piston surrounding and carried by said member and of larger area than the valve piece and dividing the casing into an upper and a lower pressure chamber, the latter in communication with the inlet, a by-pass connecting the inlet with the upper pressure chamber, means to release pressure in the upper pressure chamber to the outlet side of the valve, a sleeve surrounding the main valve piece and upstanding member, with a restricted liquid passage between said sleeve and valve piece, said sleeve being movable relatively to the valve piece and normally seating against a part in the casing to obstruct the flow of liquid, and a stud on the sleeve extending toward said reduced hollow member over said valve piece, whereby said sleeve is lifted with the main valve at the end of its opening movement, while permitting it to descend to its seat in advance of

the closing movement of the main valve piece.

7. A flush valve device comprising a casing having an inlet and an outlet and provided therebetween with an internal seat, a main valve piece coöperating with said seat to control the flow of flushing liquid and provided with a hollow neck smaller in diameter than said main valve piece, a piston movable with the main valve piece and dividing the casing into upper and lower pressure chambers, an auxiliary valve within said neck to control communication between said upper pressure chamber and the outlet, with means to normally hold the auxiliary valve closed, manual means to open said auxiliary valve, an open top shell surrounding the main valve piece and its neck and spaced from the neck to form a passage into an open communication with said inlet, there being a passage for restricted liquid flow between said shell and said main valve piece, said shell being movable relatively to the said main valve piece, and a projection on the shell abreast said neck spaced from and in the path of movement of the main valve piece.

8. A flush valve device comprising a casing having an inlet and an outlet and provided therebetween with an internal seat, a main valve piece coöperating with said seat to control the flow of flushing liquid and provided with a hollow neck smaller in diameter than said main valve piece, a piston movable with the main valve piece and dividing the casing into upper and lower pressure chambers, an auxiliary valve within said neck to control communication between said upper pressure chamber and the outlet, with means to normally hold the auxiliary valve closed, manual means to open said auxiliary valve, an open top shell surrounding the main valve piece and its neck and spaced from the neck to form a passage in open communication with said inlet, there being a passage for restricted liquid flow between said shell and said main valve piece, said shell being movable relatively to the said main valve piece, a projection on the shell abreast said neck spaced from and in the path of movement of the main valve piece, and means to vertically adjust said shell projection.

In testimony that I claim the foregoing as my invention I affix my signature in the presence of two witnesses, this 20th day of November, A. D. 1915.

EDWARD L. KELLAN.
